UNITED STATES PATENT OFFICE

2,599,041

APPARATUS FOR ENLARGING AND
STRAIGHTENING WELLHOLES

Clyde E. Bannister, Houston, Tex.

Application November 20, 1947, Serial No. 787,143

3 Claims. (Cl. 255—44)

1

This invention relates to apparatus for operating upon the wall of a well, as in enlarging or straightening an oil-well hole or compacting the wall of the hole.

Its chief objects are to provide inexpensive and efficient apparatus for those purposes, and to provide for facility and rapidity in the operation of such apparatus.

Of the accompanying drawings:

Fig. 1 is a vertical section showing a well hole and, in operating position therein, apparatus embodying my invention in its preferred form, parts of the apparatus being sectioned and broken away.

Fig. 2 is a section on line 2—2 of Fig. 1.

Fig. 3 is a section on line 3—3 of Fig. 1.

Fig. 4 is a section on line 4—4 of Fig. 1.

The embodiment here shown comprises an elongated structure adapted to be lowered and raised in the hole by means of a pair of cables 10, 10, secured to the respective arms of a yoke and fluid-coupling structure 11, through which a hose 12, extending from the top of the ground, is in communication with a fluid-coupling swivel 13 which supports the said elongated structure.

This structure comprises, in order from the swivel downward, a heavy inertia member 14, an oscillating-type motor 15 (which can be of the type shown and claimed in any of my U. S. Re-issue Patent No. 19,397 or my U. S. Patents No. 1,965,564, No. 2,016,667 or No. 2,254,641), and a reaming and/or compacting tool 16.

The structure as a whole, comprising those three elements, is largest in its middle region and moderately tapers toward each of its ends, so that it will find its way in a crooked hole and yet in its middle region will be large enough to rapidly cut away and/or compact the wall at one side of the hole, to straighten the hole, or to operate concurrently throughout the circle of the hole to enlarge the hole.

The motor 15 is adapted to receive its motive fluid from the hose 12 through a central passage 17 formed in the inertia member 14 and, by its operation, to oscillate its shaft 18, on which the tool 16 is fixed.

The motor's shaft 18 is hollow and through it the spent motive fluid from the motor is passed into the tool member 16, which is hollow and is formed with exhaust holes 19, 19 near its upper end and an exhaust hole 20 at the center of its rounded lower end-wall.

To provide ample flow space for the upward flow of exhaust fluid to the top of the well and to provide scraping or rubbing elements, each of the members 14, 15 and 16 is externally of longitudi-

2

nally fluted form, as shown clearly in Figs. 2, 3 and 4. The form and size of the tool, however, can be varied.

In the operation of the device, the inertia member 14, being rigid with the casing of the motor, sustains the reaction of the motor without substantial oscillating movement of its own, when the tool member 16 is relatively light, as by reason of being of thin walled construction, as here shown.

I do not wholly limit my invention, however, to an apparatus in which the member fixed to the motor shaft has relatively high amplitude of oscillation, as the motor casing and its upward continuation, as in the inertia member 14, can perform substantial reaming and/or compacting.

As the device is lowered in the hole, with the motor operating, the assembly, by reason of its double taper and its rounded lower end, can find its way, without jamming of its lower end against the wall of the hole, even in a hole having a high degree of crookedness, the reaming and/or compacting action of the flutes on the tool, and/or those on the motor casing and the inertia member, easing the passage of the assembly in the hole.

The reaming and/or compacting action is greatest at the middle region of the assembly because of its relatively large diameter in that region, and, as to salients of the wall that are on the low side of an inclined part of the hole, the suspension of the device by the cables causes gravity to be a factor for urging the device against such salients, on one side and then another of the hole, and thus makes the hole more nearly vertical in all of its parts, while straightening it, whether or not all of the hole is enlarged by the apparatus.

Flutes of more or less sharp form can be employed, according to whether a predominance of reaming or of compacting is desired, or a smooth, circular tool small enough to permit fluid to pass it in the hole, can be used for compacting the wall of the hole.

The apparatus as here shown is designed for a predominance of compacting, "plastering" or "mudding up" of the wall of the hole, and, to avoid excessive washing effect of the upwardly moving exhaust fluid the exhaust hole 20 at the bottom of the tool 16 is of smaller flow capacity than the holes 19 at its upper end. Yet it is of a size such as to provide sufficient up flow along the tool to carry cuttings and crumbs upward to the stronger current above the holes 19 and thus prevent them from settling through the water or driller's mud to the bottom of the well.

Modifications are possible without departure

from the scope of the invention as defined by the appended claims.

I claim:

1. Apparatus for enlarging and thereby straightening a previously drilled well hole, said apparatus comprising two oppositely tapered wall-engaging members of vertically elongated form, means for holding the two substantially in vertical alignment with their larger ends adjacent each other and in relatively rotatable relationship, each of the two said members being tapered to its end farthest from the other of the two said members, means for lowering and raising the assembly in the well hole, means for effecting rotatable movement of one of said members in relation to the other, and means for conducting fluid to and discharging it from a low part of the lower member, each of the two members being externally of fluted form for enlarging the hole while permitting upward flow of the fluid between the flutes. 15

2. Apparatus for enlarging and thereby straightening a previously drilled well hole, said apparatus comprising a fluid-actuated motor of the shaft-oscillating type having an elongated, tapered casing, an elongated, tapered tool secured upon the shaft of the motor, with the larger end of the motor casing and the larger end of the tool adjacent each other, means for lowering and raising the assembly in the well hole, and means for supplying motive fluid to the motor from the top of the ground, the said casing and the said

5 tool being externally of fluted form in a relatively wide part thereof for enlarging the hole while permitting upward flow of fluid between the flutes, the said tool comprising conducting means for receiving exhaust fluid from the motor and discharging it from the tool at a low part of the latter.

3. Apparatus as defined in claim 2 in which the means for lowering and raising the assembly in the well hole is flexible and is swiveled to the motor casing.

CLYDE E. BANNISTER.
